UNITED STATES PATENT OFFICE.

WILLIAM M. GENTLE, OF LOS ANGELES, CALIFORNIA.

CARBURETOR.

Application filed August 13, 1917. Serial No. 186,081.

To all whom it may concern:

Be it known that I, WILLIAM M. GENTLE, a citizen of the United States of America, residing at Los Angeles, county of Los Angeles, State of California, have invented a certain new and useful Carburetor; and I do hereby declare the following to be a full, clear, and exact description of the invention, such as will enable others skilled in the art 10 to which it appertains to make and use the same.

This invention relates to carburetors, and it consists of improvements on patents that have issued to me as follows: No. 1,060,545 15 issued April 29th, 1913; No. 1,099,547 issued June 9th, 1914; and No. 1,124,724 issued January 12th, 1915.

An object of this invention is to provide a carburetor which will alternately supply 20 light and heavy fuel to an engine as occasion may require for starting the engine in the one instance and for operating the engine in the second instance, and which will perform this work automatically and positively.

25 The carburetor is also adapted for adjustment by manual means.

An object of the invention is to make provision whereby the lighter fuel for starting the engine into operation will not receive 30 any additions of heavier fuel, which might make the lighter fuel less combustible.

In this invention provision is made whereby both light and heavy fuel are available to the carburetor and whereby the throttle 35 may be so operated that when it is so desired only the lighter fuel will be supplied to the carburetor, and when the carburetor becomes sufficiently heated to use the heavy fuel, the lighter fuel is automatically cut off and the heavy fuel turned on.

An object of the invention is to so construct the carburetor that the fuel is controlled directly by a minimized movement of a valve in making the change from one fuel 45 to the other.

An object is to cut off the priming fuel by a slight movement, and to provide means for this purpose which is highly effective in action, and is cheap and easy to construct 50 and assemble.

In this invention I provide a direct passage for delivering priming fuel to the engine; and said passage is closed to heavy fuel when the engine begins to function, and it is 55 then open to admit such fuel to the engine.

Provision is made whereby upon stopping

the engine the heavy fuel valve is automatically closed, and the priming fuel nozzle is filled with priming fuel ready for re-starting the engine

An object of the invention is to provide means whereby vapor bubbles forming in the fuel passageway between the fuel bowl and the nozzle will be broken up so that they will not discharge non-volatilized fuel 65 from the nozzle.

Another feature of invention is shown in the control of air by the throttle valve which is enclosed by a sleeve provided with contoured surfaces which enables the throttle 70 valve, on a slight initial opening movement, to open the air passageway of the priming nozzle in a greater ratio than the movement of throttle valve.

Other objects, advantages and features of 75 invention may appear from the accompanying drawings, the subjoined detail description and the appended claims.

The accompanying drawing illustrates the 80 invention.

Figure 1 is a plan view of the carburetor. Fig. 2 is a side elevation thereof.

Fig. 3 is a section on line 3—3 of Fig. 1.

Fig. 4 is a section on line 4—4 of Fig. 3.

Fig. 5 is a section on line 5—5 of Fig. 2, 85 parts omitted and parts broken away.

Fig. 6 is a section on line 6—6 of Fig. 1.

Fig. 7 is a section on line 7—7 of Fig. 1.

Fig. 8 is a section on line 8—8 of Fig. 7, 90 parts being broken away.

Fig. 9 is an enlarged view of the valve controlled by the thermostat shown in Fig. 6, the valve being shown in changed position.

Fig. 10 is a diagrammatic view of the 95 heating coils on the fuel nozzle and their associated parts.

Fig. 11 is an enlarged view of a portion of the heater showing the vapor bubbles breaking up in the helical fuel passageway. 100

The fuel bowl 11 has a fuel chamber 12 for heavy fuels such as kerosene, and a chamber 13 for light fuels such as gasoline.

These chambers 12 and 13 are separated 105 by a wall 14 that joins to a neck 15 integral with and extending upward from the bottom of the fuel bowl 11; and this neck 15 has a low speed air passage 16 therethrough (see Figs. 1, 3, 4 and 6). Within the chamber 12 there is a neck 17 integral 110 with and extending upward from the bottom of the fuel bowl, that has an opening 18

therethrough, and the two necks 15 and 17 have in part a common wall. The top of the fuel bowl 11 and, therefore each of the chambers 12 and 13 is closed by the cap 19, that has a cylinder 20 integrally connected to said cap and extending downward thereon through the neck 17 and threaded at the lower end to receive a nut 21 by means of which the cap 19 is secured to the fuel bowl 11.

Extending upward from the cap 19 is throttle neck 22 that has on the top thereof the flanges 23 having holes 24 for bolts to fasten it to the intake end of the engine inlet manifold, not shown.

The lower end of the cylinder 20 is internally threaded to receive a choke cylinder 25 formed with a hexagon 26 by which means the choke cylinder is adjusted. The upper end of the choke cylinder is contracted to concentrate the air flow around the fuel nozzle in the main air passage 27. A sleeve 28 is mounted in the neck 22; and within this sleeve is a throttle valve 29 secured to a shaft 30 that passes through both the sleeve and neck so that the sleeve is held by the shaft securely within the neck.

The sleeve 28 rests on a ledge 31 in the top portion of cylinder 20, and has a port 32 that registers with an opening 33 in the throttle neck 22. The hood 34 at the junction of cap 19 and neck 22, forms a chamber 35 open to port 32, and communicating at its lower end 36, with the slow speed air passage 16 forming thereby a passageway from the outer air to the throttle valve. A baffle plate 37 integral with sleeve 28 extends from the bottom of port 32, about one-third the way across the neck 22 when it is bent up and terminates with its upper edge 38 in light contact with the shaft 30, thus to form a partition between the slow speed air passage 16 and the main air passages below the throttle.

The inner surface of the sleeve 28 is shaped as at 39 to the path of the edge of the throttle through an angle of about thirty degrees below its axis, so that during the first part of the movement of the throttle to open port 32, the high speed air passage 27 will be closed by the throttle.

The sleeve 28 is recessed at 40 adjacent the upper edge of the rim of throttle valve 29 when it is in closed position; and the purpose of this recess is to make a quick opening between the low speed air passage 16 and the inlet manifold on a very slight opening movement of the throttle valve.

The neck 22 has above the throttle an auxiliary air inlet 41 that increases in area as it recedes from port 32. Said inlet is opened and closed, and its size is controlled by a manually operated valve 42 mounted on throttle shaft 30, and held in contact with the walls of inlet 41 by the spring 43,

the tension of which is controlled by tension nut 44. Auxiliary valve 42 is operated by auxiliary-air lever 45 independently of the throttle which is operated by throttle lever 46.

The purpose of inlet 41 and valve 42 is to supply auxiliary air to the carburetor. The combined cross-sectional area of the openings through the air passage 16 and 27 is considerably less than the cross-sectional area of the opening through the upper part of neck 22, consequently as the throttle is opened to full capacity, the auxiliary air supply is gradually increased.

The throttle lever 46 on shaft 30 is connected to the steering post of a motor driven vehicle as shown in my said former patents.

Surrounding the shaft 30 and integral with the neck 22 is a boss 47 to which is secured an adjustable throttle lever stop 48, that is described in detail in said former Patent No. 1,124,724.

A fuel level in each chamber 12 and 13 is maintained constant by similar means, each has a valve chamber 49 within which is the admission valve 50. The valve 50 is adjustably mounted on one end of the lever 51, that is mounted on a pivot 52; and on the other end of the lever 51 is mounted the float 53.

The top part of the valve chamber 49 is closed by the nut 55. Depending from the lower side of the valve chamber 49 is the stem 56 which has its lower end threaded for the nut 57. Surrounding the stem 56 is a casing 58 having a fuel chamber 59 therein, and above and below the casing 58 are the packing rings 60 and 61 by which means and the nut 57 the casing 58 is secured to the stem 56. On the casing 58 there is a threaded socket 63 into which one end of a pipe 64 is secured and the other end of the pipe is connected to a fuel supply tank not shown.

In the stem 56 there are inclined ducts 65 leading from the chamber 59 into a fuel passageway 66 in the stem 56 which latter passageway leads to the valve chamber 49 and consequently into the fuel chambers 12 or 13 as the case may be.

On the bottom side of the fuel bowl 11 and near to the edge thereof, there is a boss 67 which has a threaded socket into which is screwed one end of a valve casing 68, see Fig. 7. The other end of the valve casing 68 is threaded and screwed into a socket 69 which is near to one end of a heater 70. Near to the opposite edge of the bottom of the fuel bowl 11 is a depending flange 71 which has a hole therethrough that registers with a hole in an upwardly extending flange 72 near to the other end of the heater 70, and these flanges are secured together by the bolt 73, by which means the heater 70 is secured to

the fuel bowl 11. The heater 70 consists of the exterior and interior cylinders 74 and 75 that are held together by the end caps 76 that are screwed against the packing 6 rings 77 to prevent leakage from the helical fuel passageway 78 that is between the cylinders 74 and 75.

One end of the helical fuel passageway 78 is in communication with the fuel chamber 10 12 through fuel passageway 79 that extends through valve casing 69 and by the controlling valve 80. The other end of the helical fuel passageway 78 is in communication with the discharge end of the main 15 fuel supply nozzle 81 through passageway 82. Said nozzle 81 is mounted centrally in a boss on the upper side of the heater 70, and is held centrally in the main air 20 passageway 27 with the discharge end slightly higher than the level of the fuel in the chamber 12.

The caps 76 have threaded openings into which are screwed ends of the pipes 83 and 84 respectively. Pipe 83 is connected to the 25 exhaust manifold of the engine not shown and pipe 84 opens to the outer air. By this means heat is conveyed from the engine to heater 70.

Near the center of chamber 13 and on the 30 bottom thereof is a threaded nipple 85 to which is attached coupling 86, that holds pipe 87 with its opening 88 in register with an opening 89 in the nipple 85, see Fig. 6.

The bottom end of the pipe 87 is screwed 35 into a socket 90 near the outer end of a valve casing 91, that contains a chamber 92 that is in communication with chamber 13 through passageway 88. The inner end of valve casing 91 is threaded, and to this 40 threaded end is attached one end of pipe 93, said pipe having its other end provided with a left hand thread that screws into a socket 94 on the heater 70, and the opening through the pipe 93 registers with an opening 5 into the fuel passageway 82 at the lower end of the nozzle 81.

Near the inner end and on the upper side 45 of the valve casing 91 is a threaded socket 95 into which is screwed the lower end of the low speed nozzle 96 that has there-through the fuel passageway 97, that is in communication with chamber 92. The connection of the fuel nozzle to the valve casing holds it central in the primary air passageway 16 with its discharge end at a slightly higher level than the fuel in the chamber 13. Within the chamber 92 there is slidably mounted the conical valve 98, that is attached to one end of the rod 99. 50 This rod extends through the elongated plug nut 100 that has on the outer end thereof the packing nut 101, and this elongated nut 100 forms a sliding bearing for rod 99 and holds it central to the axis of cylindrical 55 casing 91 so that the reciprocating conical

valve 98 can move in said casing 91 without its sharp edge wearing on the inside wall of said valve casing.

Near to the other end of the rod 99 there is a pin 102 that extends through a slot 103 on one end of the forked lever 104. The other end of this lever is pivoted on the pin 105 of the lug 106. The lug 106 is integral with the cylinder 107 and near to one end thereof; and the other end of the cylinder 107 has an internal thread by which it is attached to an extension 108 on the side of the heater 70; said extension 108 has a threaded socket 109 into which is screwed one end of the expandible rod 110. The rod 110 has its other end extending through an opening in the wall 111 of the cylinder 107, and the packing ring 112 and engages with lever 104; and the loose end of rod 110 is squared for a wrench by which means it is screwed into or out of the socket 109 and thereby adjusted to properly engage lever 104. An adjustable spring 113 holds the lever 104 in contact with the outer end of rod 110. The cylinder 107 has on opposite 85 sides the threaded sockets 114, 116 to which are attached the ends of the pipes 115, 117.

The other end of the pipe 115 is connected to the exhaust manifold of the engine not shown and the other end of pipe 117 opened 90 to the outer air so that the exhaust will transmit heat from the engine to cylinder 107 and thereby heat the rod 110.

This rod 110 in expanding moves the lever 104 and consequently moves the reciprocating conical valve 98.

The slide valve 98 is constructed of hardened metal and formed so that its base end 118 is an exact sliding fit in the cylindrical chamber 92, and the beveled portion of the valve ground down so that it joins to the base with a sharp edge.

The object of the valve construction is to provide in the chamber 92 a movable partition that will separate the fuel entering the chamber through the pipes 88 and 93 and also provide a valve requiring a relatively small movement to cross the opening in the bottom of fuel nozzle 96 and gradually change from light to heavy fuel. As seen in Fig. 6 the valve 98 is normally held in position in which the passageway in pipe 93 to chamber 92 is closed; and the passageway 88 through the chamber 92 to passageway 97 in the nozzle 96 is fully opened. It can also be seen in Fig. 6 that the sharp edge of the base 118 of the valve 98 is in exact alignment with a plane abutting the base 118 and tangent to the opening through fuel nozzle 96, and consequently the slightest movement of combined conical and slide valve 98 from position in Figs. 6 to 9 will open the passageway 97 to fuel passing through pipe 93. As valve 98 moves from the position in Figs. 6 to 9 the supply of gasoline will be gradually 120 12 30

cut off and kerosene supplied to nozzle 96.

A manual means is shown for cutting off the priming fuel, which means consists of a pin 119 in the end of the rod 99 that is connected to the slotted end 120 of an operating rod 121 that extends to any convenient point.

The slot 120 enables the rod 99 to be freely moved by the thermostat without interference of the rod 121.

10 The nozzles 81 and 96 are electrically heated (see Figs. 6, 7 and 10) each nozzle is wound with about eight inches of high resistance wire that is properly insulated from the nozzles, and these windings connected to a 15 battery or electrical generator. As seen in Fig. 10 the nozzle 81 has thereon the resistance coil 122 one end of which is connected to the binding post 123. The other end of said coil is connected to the binding post 124. To 20 the post 124 there is secured one end of the wire 125 the other end of which is secured to the binding post 126 to which latter is secured one end of the nicrome coil 127 on the nozzle 96. The other end of the coil 127 is 25 secured to the binding post 128 to which post is also attached one end of the wire 129, and the other end of the latter is attached to the battery 130. On the other side 30 of the battery 130 there is attached one end of the wire 131, the other end of which is attached to one contact of the switch 132, and the latter can be located in any desirable or convenient place. To the other contact of the switch 132 there is attached one end 35 of the wire 133 the other end of which is secured to the binding post 123, thus completing the circuit.

As seen in the drawings the heater and the electrical heated nozzles are intentionally 40 spaced away from any direct contact with the fuel bowl, the object of which is to prevent heating the fuel while in the chambers 12 and 13.

As is well known, the heating of the fuel 45 in these chambers will create a vapor that will seriously interfere with an even flow of fuel into and out of the chambers. In the event that vapor is formed in the chambers a means is provided for removing and dis- 50 charging it into the outer air in close proximity to the inlets of the air passageways where suction from the engine will draw it into the cylinders. This means consists of a boss 134 that has a threaded socket 135 and into which is screwed the valve casing 136. This casing is provided with a passageway 137 that registers with a passageway 138 in the thickened portion of the wall 14 between the chambers 12 and 13. The pass- 55 ageway 138 leads into a cross passageway 139, one end of which opens into the chamber 12 and the other into the chamber 13.

The passageway 137 is controlled by the 60 needle-valve 140 which is located in the upper part of the valve casing 136. To the

lower part of the valve casing 136 there is secured one end of the flexible pipe 141 the opening of which is in communication with the passageway 137. The pipe 141 is bent inwardly until its open end is in close proximity to the inlet of the air passageway 16 so that vapor forming in either chamber 12 or 13 will escape to the outer air unaffected by engine suction except that the escaped vapor will mix with air and be taken into the 75 engine by suction through the carburetor.

In the upper part of the air passageway 16 there is secured a plate 142 with a reduced opening therethrough that is adapted to direct the incoming air current around 80 the discharge end of the starter nozzle 96.

As previously stated the fuel passing from the chamber 12 to the heater 70 (see Figs. 1, 2, and 7) is controlled by the valve 80. This valve 80 is operatively connected by 85 a valve stem 143 to an arm 144. To the outer end of the arm 144 there is pivotally secured one end of an adjustable connecting rod 145, and the other end of this rod is pivotally connected to one end of the 90 arm 146 which is integral with the throttle lever 46.

By means of the adjustable rod 145 the 95 position of valve 80 can be changed relative to the position of the throttle valve.

As seen in Figs. 7 and 11 the helical fuel passageway 78 is formed by a groove substantially semicircular in cross section, the purpose of which is to form a conduit of cheap construction in which bubbles 150 of 100 vapor formed by heat will not be able to entirely fill the passageway 78 and thereby carry in front of them a large quantity of unvolatilized fuel. As seen in Fig. 11 the bubbles 150 that are formed in the oil are 105 carried against the interior wall of the casing cylinder 74. One bubble 150 is shown as large as it can form in the passageway without entirely filling the latter, and the adjoining bubble is shown broken into a 110 plurality of little ones.

In operation the chamber 12 is used for heavy fuel such as kerosene, and the chamber 13 used for light fuel such as gasoline. The electrical heater is put in operation to 115 warm the nozzles and surrounding air; after which the throttle lever is moved to a starting position.

When the throttle lever 46 is moved from the first to second dotted position in Fig. 120 8 the throttle valve will move to open the air passageway 16 to the engine, so that fuel from the starter nozzle 96 and chamber 13 will be taken into the engine; and the other air passageway 27 and nozzle 81 125 remain closed until the throttle is further actuated. After the engine is started and the heater 70 put into action to vaporize the liquid fuel and also the thermostat which is attached thereto is active, the slide valve 130

98 will be actuated to cut off the starting fuel in chamber 13, and open nozzle 96 to the heavy from the chamber 12. When more power is needed the throttle lever 46 is moved from the second dotted position toward the full line position of Fig. 8 which movement will open both passageways 16 and 27 to the engine.

What I claim as my invention, and desire to secure by Letters Patent is:

1. In a carburetor; two fuel supply chambers for heavy and light fuel respectively; a low speed nozzle normally in communication with the supply of light fuel; and a valve which may be operated to shut off the connection between the low speed nozzle and the supply of light fuel and to open the connection to the supply of the other fuel.

2. In a carburetor for supplying a mixture of air and fuel to an engine; two fuel supply chambers for heavy and light fuel respectively; a low speed nozzle normally in communication with the supply of light fuel and adapted to supply the light fuel to the mixture for starting an engine; and manual means for discontinuing the supply of light fuel, and supplying the heavy fuel to the mixture.

In testimony whereof, I have signed my name to this specification in the presence of a subscribing witness at Los Angeles, county of Los Angeles, State of California, this 8th day of August A. D. 1917.

WILLIAM M. GENTLE.

Witness:

ELLA SCOTT.
